(57) **CLAIM**

We claim a cover for a mounting bracket for a retractable shade, as shown and described.

DESCRIPTION

FIG. 1 is a reduced isometric view of a cover for a mounting bracket for a retractable shade showing our new design, the broken line showing of the retractable shade, brackets, and additional cover is included for the purpose of illustrating environmental structure and forms no part of the claimed design.

FIG. 2 is an enlarged isometric view thereof, the broken line showing of the mounting bracket is included for the purpose of illustrating environmental structure and forms no part of the claimed design.

FIG. 3 is a front isometric view thereof.

FIG. 4 is a rear isometric view thereof.

FIG. 5 is a front elevation view thereof.

FIG. 6 is a top plan view thereof.

FIG. 7 is a left side view thereof.

FIG. 8 is a right side view thereof.

FIG. 9 is a rear elevation view thereof; and,

FIG. 10 is a bottom plan view thereof.
